ELECTRICAL CONNECTION MEANS

William Schmid, Bronson, Mich., assignor to
 Kingston Products Corporation, Kokomo, Ind.,
 a corporation of Indiana

Application June 21, 1937, Serial No. 149,512

4 Claims. (Cl. 173—328)

This invention relates generally to electrical connection means, and more particularly has to do with means for resiliently retaining a terminal.

One object of the invention is to provide connection means including in combination, a shell, terminal receiving means, resilient means, and an insert, all of which are preferably assembled to a mounting plate preferably of insulating material to constitute a unit, which may be mounted on a support in relation to some electrical device.

Another object is to design and construct the insert whereby its upper extremity acts as a detent, which cooperates with the terminal receiving means to resiliently retain a terminal.

Another object is to provide the lower extremity of the said insert with means whereby a conductor may be either fixedly or resiliently detachably connected thereto.

A further object is to provide the shell with means for holding the parts of the unit in assembly with the mounting plate, and also with means whereby the complete unit may be permanently connected to some support or device.

A still further object of the invention is to construct a connection means which may be economically manufactured commercially, and one which is durable and effective in operation mechanically and electrically.

Referring to the drawing wherein the parts of the device forming the invention are identified by numerals:

Figure 1 is an enlarged vertical sectional view of the unit as applied to a support;

Figure 2 is an upstanding view, on a smaller scale, showing the unit prior to being assembled with the support shown in Figure 1;

Figure 3 is a section, on a reduced scale, taken substantially on line 3—3 of Figure 1, clearly showing in detail a part of the insert member above referred to;

Figure 4 is a bottom view, on a very small scale, of the assembly shown in Figure 1;

Figure 5 is a top view of a modified form of the invention;

Figure 6 is an upstanding view of the modification shown in Figure 5;

Figure 7 is an enlarged vertical sectional view of the unit in Figure 6 assembled with a support; and,

Figure 8 is a section taken substantially on line 8—8 of Figure 7 showing the manner in which the lower extremity of the insert is adapted to detachably resiliently retain a terminal.

It will be evident upon referring to the draw-

ing that the connection means is of such a character that electrical connection can be made therethrough from one side of a support to the opposite side.

In the drawing, 1 indicates a mounting plate preferably of insulating material; 2, a cylindrical shell; 3, a moveable terminal receiving means; 4, a resilient means in the form of a coiled compressible spring; and 5, is a stationary insert, all of which are preferably assembled to the plate whereby to constitute the unit shown in Figure 2. This unit is adapted to be permanently secured to a suitable support as shown in Figure 1, and is insulated therefrom.

Considering in detail the principles of design and construction, the plate 1 of insulating material is provided with two arcuate slots 6, diametrically arranged, and a rectangular slot 7 midway therebetween.

The shell 2 is of metal, and is preferably in the form of an inverted cylindrical cup, and its upper extremity is provided with a rectangular aperture 8 through which the terminal receiving means 3 extends. The side wall of the shell is preferably provided with a pair of outwardly extending circular flanges 9, diametrically arranged, which bear against the upper surface of the plate 1; and the wall is further formed with a pair of elongated continuations 10, which are diametrically arranged between said flanges 9, and extended through the arcuate slots 6 in the plate 1. The wall is also provided with a pair of relatively short lugs 11 adjacent the continuations 10, and these also extend through the arcuate slots 6, and when the parts of the unit are assembled these lugs 11 are bent inwardly laterally against the under surface of the plate 1 as clearly shown.

The terminal receiving means 3 is made of metal formed to provide a tubular body 12 preferably rectangular in cross section, having a substantially cylindrical transverse terminal receiving aperture 13 adjacent its upper extremity, and a pair of laterally extending flanges 14 at its lower extremity. More specifically the body 12 includes a pair of channel portions 15 joined together by a connecting loop 16, the portions 17 thereof forming two of the walls of the body. These portions 17 as indicated at 18 terminate short of the loop 16, and are so designed adjacent the loop to conform to and form a part of the cylindrical terminal receiving aperture, so that a terminal of the character shown in Figure 7 may be easily inserted into the aperture. Rotation of the terminal receiving means 3, or body 55

12 with respect to the shell 2 is avoided, since the means extend through the rectangular aperture 8 in the shell 2.

The insert 5, above mentioned, extends through 5 the rectangular slot 7 provided in the plate 1, and the upper extremity 19 of the insert is of a size whereby the same will extend within the tubular body 12. A pair of rounded projections 80 are struck outwardly from the opposite sides 10 of the upper extremity 19, and these engage the walls of the body to center the insert longitudinally therein. The end of the upper extremity 15 of the insert provides a detent to hold the terminal that is adapted to be inserted into the cylindrical aperture, and to better accommodate a terminal, an arcuate seat 20 is provided adjacent the upper end of the extremity.

The insert intermediate its ends, is also provided with a pair of spaced apart stops 21 projecting laterally from one side thereof, and these 20 abut the upper surface of the plate 1, and serve to position the seat 20 in a predetermined relation with respect to the terminal receiving aperture 13.

25 The compressible spring 4 encircles the body 12 forming the terminal receiving means, and as clearly shown, one end of this spring engages the upper end extremity of the shell 2, and its opposite end engages the laterally extending flanges 30 14 in a manner whereby to normally urge said flanges against the stops 21 provided on the insert, and holds the parts in a predetermined relation, particularly the body in an erect position. This is particularly true when the unit 35 shown in Figure 1 is secured in an inverted or horizontal position to some mechanism or support. When a terminal of the character shown in Figure 7 is inserted into the terminal receiving aperture, the terminal receiving means 3, or in other words, the body 12 will be urged outwardly against the action of the spring, and when the groove 22 in the terminal cooperates with the seat 20 in the insert, the body 12 will substantially return to its original position, forcing the terminal against the insert in order to 40 provide a good electrical connection.

Although the lower extremity 23 of the insert 5 is preferably of a greater width than the upper extremity, it may be otherwise constructed. 50 It is to be noted that the lower extremity is preferably of a length whereby to extend entirely through and clear of the means employed for fastening the unit with respect to the support shown in Figure 1, and is provided with an aperture 24 through which a conductor may be inserted and suitably secured, such as by soldering; and by reason of the stops 21 on the insert, any accidental pull on a conductor secured to the insert will not in any way release 55 a terminal located in the terminal receiving aperture 13.

Referring to Figure 1, it will be clearly evident that the unit shown in Figure 2 is adapted to be mounted on a support 25 adjacent to some electrical device. The support is provided with a circular aperture 26, and a washer 27 of insulating material is preferably arranged adjacent the lower surface of the support, and is so constructed and arranged that the annular reduced portion 28 thereof fits snugly within the aperture 26; and the continuations 10 formed on the shell 2 are adapted to project through a rather large opening 29 provided in the washer 27, and through arcuate slots 30 provided in a 75 metal washer 31, and the ends are then clinched

outwardly and over on the washer 31, as shown, in order to hold the unit in a fixed position on the support. The lower extremity 23 of the insert is, of course, adapted to project through a rectangular slot 32 provided in the washer 31. 5

Referring to the modification of the invention shown in Figures 5 through 8, Figure 6 discloses a unit corresponding in many respects to the unit above described, except that the lower extremity of the insert is provided with means 10 whereby to detachably resiliently retain a terminal.

In this arrangement, the unit includes a plate 50 of insulating material, a cylindrical shell 51, a coiled spring 52 surrounding the terminal receiving means 53, and an insert 54, all of which are assembled together in substantially the same manner as above described, the shell among other things being provided with flanges and lugs corresponding to those above referred to. 20

The insert as here shown is comprised of a single strip of sheet metal which is folded back upon itself as indicated at 55 in order to provide a rounded detent portion 56 that is adapted to cooperate with the groove 22 in the terminal. By reason of the offsets, shoulders are provided on the insert, and these position the detent 56 in a predetermined position with respect to the terminal receiving aperture 70. The lower extremity of the insert 54 is preferably 30 provided with three offset elongated resilient fingers 57 and 58. The two fingers 57 are of the same character, while the finger 58 is shorter, of a greater width, and is provided with a detent 59 adjacent its free end. As clearly shown, 35 the plate 50 is provided with suitable arcuate slots 60 and 61, through which the fingers 57 and 58 project. All of the fingers 57 and 58 function to resiliently hold the terminal in relation thereto, and the detent 59 provided on the 40 finger 58 is adapted to cooperate with the groove 22 in the terminal and the arrises 63 on the fingers 57 engage the spaced apart lands 64 and 65 on the terminal 62. Thus a good electrical connection is provided between a terminal that 45 is adapted to be inserted into the terminal receiving aperture 70, and the terminal 62 adapted to be held by the lower extremity of the insert.

This modified form of unit is also adopted to be mounted on a support such as 66, which has 50 an aperture therein, and it has also been found desirable to use an insulating washer such as 67 without including a metallic washer such as 31 above referred to. As clearly shown the washer 67 is provided with an aperture of a relatively 55 large diameter in order that the fingers 57 and 58 may flex without interference when the terminal 62 is being connected to or disconnected therefrom. The continuations 68 formed on the shell 51 are, of course, adapted to extend through 60 the aperture in the support 66, and the aperture provided in the washer 67, and the ends of the continuations 68 are clinched outwardly and over against the under surface of the washer 67 in 65 order to hold the unit in a fixed position with respect to the support.

Having thus described my invention, it is obvious that various immaterial modifications may be made in the same without departing from 70 the spirit of the invention; and, therefore, I do not wish to be understood as limiting myself to the exact forms, constructions, arrangements, and combination of parts, herein shown and described. 75

What I claim and desire to secure by Letters Patent is:

1. Electrical connection means, including a plate, means for receiving a terminal carried by said plate, a sheet metal insert loosely operatively related to said receiving means with one extremity of the insert acting as a detent to hold a terminal adapted to be placed in said receiving means, resilient means pressing said insert against said plate and maintaining said insert erect with respect to said receiving means and operatively related to said receiving means for holding a terminal placed therein in electrical engagement with said insert, the other end of said insert being extended and provided with flexible means whereby to resiliently retain a terminal. 10
2. Electrical connection means; including in combination; a mounting plate; means for receiving a plug conductor terminal carried by said plate; a sheet metal insert loosely mounted on said plate having an upper extremity, and a flexible lower extremity extended through said plate whereby a conductor may be detachably connected thereto; stop means provided on said insert engaging said plate and abutting said receiving means whereby to arrange said upper extremity in a predetermined relation with respect to said receiving means and an arrangement whereby accidental pull on a conductor attached to said lower extremity will not affect the position of said insert to release a terminal placed in said terminal receiving means and resilient means normally holding said receiving means in engagement with said stop and said stop against said plate. 20
3. Electrical connection means including an apertured metal support, a plate of insulating material disposed on each side of said support covering said aperture, a cylindrical shell arranged on one side of said support and provided with flanges in abutment with one of said plates, means extending through said plates and said aperture in said support and bent laterally with respect to one of said plates to secure said shell in place, an aperture provided in said shell, a tubular body projecting through said aperture in said shell and provided with a terminal receiving aperture arranged transversely to the axis 30 of said body, flanges provided on said body, an elongated substantially flat insert member extending within said tubular body and through said plates and through the aperture in said support, the upper end of said insert intersecting said terminal receiving aperture and provided with a seat adapted to cooperate with a terminal, the lower end of said insert being extended clear of said support whereby a conductor may be secured thereto, abutment means provided on said insert member engaging said one of said plates of insulating material, and spring means pressing the flanges of said body against said abutment means and the latter against said one plate to maintain the upper and lower ends of said insert as specified, said spring means also acting to press a terminal placed in said terminal receiving aperture into engagement with the seat provided in said insert. 35
4. Electrical connection means including an apertured support, a plate of insulating material disposed on each side of said support covering said aperture, a cylindrical shell arranged on one side of said support and provided with flanges in abutment with one of said plates, means extending through said plates and said aperture in said support and bent laterally with respect to said plates to secure said shell in place, an aperture provided in said shell, an arched body projecting through said aperture in said shell and provided with a conductor receiving aperture, projecting means provided on said body, an elongated insert member extending within said arched body and through said plates and through the aperture in said support, the upper end of said insert intersecting said conductor receiving aperture whereby to cooperate with a conductor adapted to be inserted into said aperture, the lower end of said insert being extended clear of said support whereby a conductor may be secured thereto, abutment means provided on said insert engaging one of said plates of insulating material, and resilient means pressing the projections of said body against said abutment means and the latter against said one plate whereby to maintain the upper and lower ends of said insert as specified, said resilient means also acting to press a terminal placed in said terminal receiving aperture into engagement with the upper end of said insert. 40

WILLIAM SCHMID. 50
